DRAFT REGULATOR

John W. Miller and Basil D. Figg, Lansing, Mich.,
assignors to Motor Wheel Corporation, Lansing,
Mich., a corporation of Michigan

Application July 2, 1945, Serial No. 602,882

4 Claims. (Cl. 236—45)

1

This invention relates to improvements in draft regulators for combustion apparatus.

The principal object of the present invention is to provide a draft regulator of especially simple and economical construction.

Another object is to provide a draft regulator, the principal parts of which can be pressed from sheet metal.

Still another object is to provide a draft regulator in which the frame for supporting the damper blade can be pressed from a single piece of sheet metal.

A further object is to provide a draft regulator having novel means for mounting an adjustable weight.

These objects will appear more fully as the description of the invention proceeds.

In the drawings:

Figure 1 is a front elevational view of a draft regulator embodying the invention;

Figure 2 is a cross-sectional view taken on substantially the line 2—2 of Figure 1;

Figure 3 is an enlarged fragmentary front elevational view of a portion of the frame shown in Figure 1;

Figure 4 is a fragmentary side elevational view of the structure shown in Figure 3; and

Figure 5 is a fragmentary cross-sectional view taken on substantially the line 5—5 of Figure 3.

The draft regulator is of the type adapted to be mounted on the flue outlet or chimney of a conventional heating device such as an oil burning space heater or furnace, not shown. A collar 10 is adapted to be attached to the flue outlet at one end (not shown), and carries the draft regulator at its other, and open, end.

The draft regulator comprises a frame 11 and a damper blade 12 pivotally mounted in a vertical position on a horizontal axis in the frame 11. The damper blade carries a balance weight assembly 13 for regulating the draft. The construction and operation of these parts will more fully appear presently.

The frame 11 is an annular ring of generally Z shaped configuration in cross section (see Figure 2) pressed from a single sheet of metal. It has a cylindrical portion 14 which telescopes within the open end of the collar 10, and a radially outwardly extending flange 15 which abuts the free end of the collar. At the inner end of the cylindrical portion 14 is a substantially plane radial portion or flange 16 provided with a relatively large opening therein to receive the damper blade 12. For the greater portion of its circumference the inner edge of the flange 16 is circular. However, at

2

opposite sides of the ring above the center thereof the inner edge of the flange is straight and is provided with flat axially extending shoulders 17.

A pair of axially inwardly extending shallow depressions 18 are pressed in the flange 16 adjacent and radially outwardly of the shoulders 17 for a purpose which will appear presently. The shoulders 17 are extended axially outwardly a substantial distance and terminate at their axially outer extremities in radially extending stop lugs 19. Generally oval apertures 20 are formed in the shoulders 17 with their longer axes in a horizontal position. The centers of the apertures 20 are located in the plane of the flange 16.

Somewhat below the lugs 19 are two more stop lugs 21. These lugs are offset axially outwardly from the flange 16 a distance approximately equal to the thickness of the damper blade 12. The lugs 21 extend radially inwardly from the flange 16.

The damper blade is a single sheet metal stamping having a shape the same as that of the opening in the frame 11 but very slightly smaller than the opening. At opposite sides of the blade the metal thereof is slit at 22 and is pressed forwardly and rearwardly to provide pockets to receive pivot shafts 23. The pivot axis is located above the center of the blade and in line with the apertures 20 in the frame when the blade is in the frame.

Somewhat above the center of the blade the metal thereof is pressed axially outwardly to provide a circular recess 24. The center of the recess is located above the pivot axis, and an opening is punched in the center of the recess.

The balance weight assembly 13 comprises generally a support 25, a shaft 26, a weight 27 and a knob 28. Preferably the support is extruded from relatively soft metal. It has a hub 29 and a flange 30. The hub has a hole therethrough to receive the shaft 26 and the wall of the hole is provided with a helical groove 31. The flange 30 may be riveted or otherwise secured to the outer surface of the recess 24 with the hub extending through the opening therein.

The shaft 26 is rotatably mounted in the hole in the hub 29. Intermediate the ends of the shaft is a cylindrical recess which receives a coil spring 32 and a hemispherical headed plunger 33. The latter fits in the groove 31 and is held therein by spring 32. A stop pin 34 is threaded into the shaft 26 in spaced relation to the plunger 33.

The weight 27 is provided with a recess 35 to receive the hub 29 when the weight is adjusted to a position next to the blade 12. The weight 27 is secured on the axially inner end of shaft 26

by peening over the end of the shaft. The knob 28 is attached to the outer end of the shaft. Preferably the knob is shaped like a pointer, or carries a pointer which cooperates with dial figures on the flange 30 to indicate the setting of the weight.

Since the damper blade is pivoted above center, the air pressure on the lower portion of the blade is greater than that on the upper portion so that the lower portion tends to swing inward and the upper portion outward when there is any draft in the flue outlet, to admit air to the flue. The admission of air to the flue tends to reduce the draft on the burner. Any tendency for the draft to fluctuate is compensated for by the damper blade swinging to admit more or less air to the flue and thereby maintain a constant draft. The damper swings easily without appreciable friction as the pivot shafts 23 roll the bottom edges of the oval apertures 20.

The draft may be regulated by rotating the knob 28. That causes the weight 27 to move toward or away from the plane of the blade. When the weight is closest to the blade the latter is statically balanced and offers no resistance to swinging. Where the weight is moved away from the blade it counteracts the tendency of the air pressure to swing the blade, and in its position farthest from the blade the weight offers its greatest resistance to swinging movement of the blade, thus maintaining the greatest draft on the burner.

The stops 19 limit the opening movement of the damper blade, as the latter strikes the upper edges of those stops when the blade has turned through a little less than 90° from its vertical position. The stops 21 prevent the damper from swinging in the opposite direction from the vertical, in case a sudden back draft should tend to create such a movement of the blade.

From the foregoing it will be apparent that the present invention provides an extremely simple and economical draft regulator, as the blade and frame can be formed as one piece sheet metal stampings. Also, the balance weight assembly can be cheaply and easily fabricated and assembled.

The scope of the invention is indicated in the appended claims.

We claim:

1. A draft regulator comprising a one piece frame provided with a central opening, a damper blade substantially filling said opening, means pivotally connecting said damper blade to said frame on an axis offset radially from the center of the blade and dividing the latter into a minor portion and a major portion, a balance weight assembly mounted in the minor portion in spaced relation to the pivot axis, said balance weight assembly comprising a hub having a bearing therein and a helical groove in the wall of said bearing, a shaft rotatably mounted in said bearing, said shaft having a spring pressed pin therein with the free end of the latter seated in said groove, and a weight fixedly mounted on the axially inner end of said shaft.

2. A draft regulator comprising a one piece annular frame having a circumferentially continuous substantially plane portion provided with a central opening, said plane portion having a pair of axially inwardly extending depressions therein offset radially from the center of said frame, the radially inner sides of said depressions being defined by axially outwardly extending shoulders, said shoulders having aligned openings therein, a damper blade substantially filling said opening, pivot shaft means attached to said damper blade and received in the openings in said shoulders for pivotally mounting said damper blade in said frame, and stop means integral with said frame for limiting the pivotal movement of said blade in both directions from said plane portion.

3. A draft regulator comprising a frame provided with a central opening, a damper blade substantially filling said opening, means pivotally connecting said damper blade to said frame on an axis substantially in the plane of the blade, a balance weight assembly connected to the blade in spaced relation to the pivot axis of the latter, said balance weight assembly comprising a hub member having a bearing therein, a shaft member rotatably mounted in said bearing, one of said members having a substantially helical guideway therein, the other member having a spring pressed follower, one end of said follower being seated in said last named member and the other end seated in said guideway, and a weight fixedly mounted on one end of said shaft member.

4. A draft regulator comprising a frame provided with a central opening, a damper blade substantially filling said opening, means pivotally connecting said damper blade to said frame on an axis substantially in the plane of the blade and offset radially from the center of the latter whereby to divide the blade into a minor portion and a major portion, a balance weight assembly mounted in the minor portion in spaced relation to the axis of the blade, said balance weight assembly comprising a hub member having a bearing therein, a shaft member rotatably mounted in said bearing, one of said members having a substantially helical guideway therein, the other member having a spring pressed follower, one end of said follower being seated in said last named member and the other end seated in said guideway, and a weight fixedly mounted on one end of said shaft member.
